DOOR LOCKING MECHANISM

Anthony Schneider, Silverton, Ohio

Application November 13, 1936, Serial No. 110,720

7 Claims. (Cl. 70—269)

This invention relates to door control means for use in emergencies such as robbery. The general object of the invention is to provide means for locking a door, instantly, from a location remote therefrom if desired, and to maintain the door locked for a substantial yet short period of time such as a few minutes, and thereupon automatically unlock the door. The invention is particularly adaptable for doors of the revolving type and another object of the invention is to provide a mechanism suitable for such a door.

The exact nature of this invention together with further objects and advantages thereof will be apparent from the following description taken in connection with the accompanying drawing, in which Figs. 1 and 2 are elevation and plan views respectively showing an embodiment of the invention applied to a revolving door, parts being broken away to show details of construction, the mechanism being in unlocked position; Fig. 3 is an enlarged sectional detail as in the plane of line 3—3, Figs. 1 and 2, showing parts of the control mechanism; Fig. 4 is a view similar to Fig. 3 but showing the parts in locked position; Fig. 5 is a horizontal section as in the plane of line 5—5, Fig. 1; Fig. 6 is a vertical section as in the plane of line 6—6, Fig. 1.

With reference now to the drawing the door, which may be of the usual four-leaf design to be cooperative with a cylindrical housing as indicated in Figs. 1 and 2, mounted for rotation upon a vertical axis, is provided at its upper end with a circular member 1 having teeth as shown.

Bolt means are provided for engagement with the teeth of the member 1, to lock the door by its securing against rotation. For mounting the bolt means a bracket 2 is arranged above the door and the bolt means mounted in the bracket for movement between locking and unlocking positions. The bolt means here shown includes a shank member 3 having at its end a tongue member 4 which latter projects through the ceiling of the door housing to be engageable with the locking teeth of the door. These teeth being of rectangular section the tongue member of the bolt means is slidably mounted upon its shank member as by the pin and slots illustrated in Figs. 1 and 6, and a spring 5 arranged to be effective between the tongue member and a suitable flange projection on the shank member, to yieldably maintain the tongue member upon the shank member in the most extended position permitted by the pin.

The bolt means is in itself balanced by a unit 55 toward locking position as here shown, both by

gravity and by a compression spring 6 effective between a part of the bracket 2 and the flange on the shank member 3 which serves to back the spring 5. The arrangement is obviously such that when the bolt shank 3 is released to the action of the spring 6, if a notch in the member 1 lie opposite the bolt tongue 4 as in Figs. 5 and 6, the bolt will immediately enter the notch, whereas if under the conditions of bolt release a tooth of the member 1 lie opposite the bolt tongue, the spring 5 will yield but as soon as the door be turned sufficiently to register a notch of the member 1 with the bolt tongue, the spring 5 will cause the latter to enter such notch.

For operation of the bolt means the shank part 3 is provided with a projection 3a arranged to be engaged by a bolt control member 7 here illustrated as a crank pin projecting from a gear 8 mounted for free rotation upon a bracket 9. The arrangement is such that when the gear 8 is rotated, as counterclockwise in Fig. 6, the member 7 will travel a circular path, in a short uppermost stretch of which engagement will be had with the bolt projection 3a to move the bolt against the spring 6 to the unlocked position of Figs. 1 and 6, whereas in the greater portion of such path of the member 7 the bolt will be maintained in locked position by its spring 6.

Means are provided for so driving the gear 8 and thus the member 7 and at different speeds in the two stretches of its travel. For high speed operation of the gear to quickly release the bolt, a high speed motor 10 is provided, mounted as upon the bracket 9 and having a pinion 11 meshing with the gear.

For low speed operation through the long stretch of the member 7, a low speed motor 12 is provided also mounted on the bracket 9, and driving the gear 8 through speed reducing means such as the pinion 13, gear 14 and pinion 15.

For control of the motors 10 and 12 and thus of the locking of the door, switch means are provided in the circuit indicated in Fig. 1. Such switch means includes a pair of automatic switches generally indicated at 16 and 17, conveniently mounted on the bracket 2, and a switch 18 which may be located remotely from the door for convenient access to the operator.

The switches 16 and 17 are controlled as by a disk 19 mounted in the bracket 2 for oscillatory adjustment as indicated in Figs. 1, 3 and 4, in timed relation with the bolt. The face of the disk 19 is provided with a pair of depressions 20, 21, registerable with ball-headed plungers 20a and 21a respectively, on the switches 16 and 17.

These switches are so arranged, as by the springs illustrated in Fig. 1, that when the disk 19 is in the position of Fig. 3 with its depressions in registry with the switch plungers, the switch 16 will be open and the switch 17 closed, whereas when the disk assumes the position of Fig. 4, with its depressions out of registry with the switch plungers, the switch 16 will be closed and the switch 17 open.

10 For operation of the disk 19 between its two positions in accordance with movement of the bolt, the member 19 is provided with a slot 22 engageable by a pin 3b on the bolt shank 3.

15 The switch 16 is arranged in the circuit to control the supply of current to the high speed motor 10 from the line L₁, L₂, as illustrated this circuit including all three of the switches. The switch 17 is arranged to control the low speed motor 12, as will appear.

20 Operation will be as follows, commencing with the parts in the position illustrated in Figs. 1, 2, 3, 5 and 6. Instant closure of the switch 18 completes the circuit of the high speed motor 10, this circuit including the switch 17 which is in closed position. Starting of the motor 10 drives the gear 8 counterclockwise, Fig. 6, to release the bolt by moving of the member 7 from under the member 3a. As the bolt drops to thus lock the door, the member 19 is shifted to the position of Fig. 4 wherein the switch 16 is closed and the switch 17 opened. Opening of the switch 17 stops the high speed motor 10 but at the same time closing of the switch 16 starts the low speed motor 12. The member 7 thus continues to travel but at slow speed through its circular path, during which time the door is maintained locked.

40 Eventually the member 7 rises to reengage the member 3a, withdraw the bolt and return the member 19 to the position of Fig. 3. This reopens the switch 16, cutting off the current from the motor 12, with the parts all returned to their original positions and the door unlocked.

45 A bell 23 or other signal device may be arranged in the circuit as illustrated to sound an alarm upon locking of the door. If desired a number of switches such as 18 may be provided at different locations, from any of which the door locking cycle may be initiated, all as will be appreciated by one familiar with the art.

50 What I claim is:

1. Door control means, bolt means for locking said door and balanced toward locking position, a bolt control member mounted for movement in a path having a short stretch wherein said bolt means is held from locked position by said member and a long stretch wherein said bolt means is released by said member, and means for causing said bolt control member to travel said path and including means for automatically stopping said member in said short stretch.

55 2. Door control means, bolt means for locking said door and balanced toward locking position, a bolt control member mounted for movement in an endless path having a short stretch wherein said bolt means is held from locked position by said member and a long stretch wherein said bolt

means is released by said member, and means for causing said bolt control member to travel said path and including means for automatically stopping said member in said short stretch.

3. Door control means, bolt means for locking said door and balanced toward locking position, a bolt control member mounted for movement in a path having a short stretch wherein said bolt means is held from locked position by said member and a long stretch wherein said bolt means is released by said member, and means for causing said bolt control member to travel said path and at a lower speed in said long stretch than in said short stretch, and means for automatically stopping said member in said short stretch. 15

4. Door control means, bolt means for locking said door and balanced toward locking position, a bolt control member mounted for movement in a path having a short stretch wherein said bolt means is held from locked position by said member and a long stretch wherein said bolt means is released by said member, motor means for causing said bolt control member to travel said long stretch at a low speed, means for stopping said motor means at the end of said travel, and 20 means for moving said member from said short stretch to said long stretch at high speed.

5. Control means for a door of revolving type comprising bolt means for locking said door and balanced toward locking position, a bolt control member positionable to hold said bolt means from locking position, and mounted for movement in a path to and from such position, high speed driving means for moving said member from said position and low speed driving means 30 for returning said member to said position.

6. Control means for a door of revolving type comprising bolt means for locking said door and balanced toward locking position, a bolt control member positionable to hold said bolt means from locking position, and mounted for movement in a path to and from such position, high speed driving means for moving said member from said position and including a remote starting control, and low speed driving means for returning 45 said member to said position and including start means automatically effective upon operation of said high speed driving means and stop means automatically effective upon attainment by said member of said position.

7. Control means for a door of revolving type comprising bolt means for locking said door and balanced toward locking position, a bolt control member positionable to hold said bolt means from locking position, and mounted for movement in 55 a path to and from such position, high speed motor means arranged to drive said member from said position and having a remote starting control, and low speed motor means arranged to return said member to said position and having control means arranged for automatically starting dependent upon operation of said high speed motor means and for stopping dependent upon attainment by said bolt control member of said position.

ANTHONY SCHNEIDER.

CERTIFICATE OF CORRECTION.

Patent No. 2,090,520.

August 17, 1937.

ANTHONY SCHNEIDER.

It is hereby certified that error appears in the printed specification of the above numbered patent requiring correction as follows: Page 1, first column, line 54, for the word "by" read as; and that the said Letters Patent should be read with this correction therein that the same may conform to the record of the case in the Patent Office.

Signed and sealed this 12th day of October, A. D. 1937.

Henry Van Arsdale.

Acting Commissioner of Patents.
